UNITED STATES PATENT OFFICE.

WELDON ROBERTS, OF MONTCLAIR, NEW JERSEY.

ERASER.

1,243,447.

Specification of Letters Patent.

Patented Oct. 16, 1917.

Application filed August 24, 1914. Serial No. 858,280.

To all whom it may concern:

Be it known that I, WELDON ROBERTS, a citizen of the United States, and a resident of Montclair, in the county of Essex and 5 State of New Jersey, have invented certain Improvements in Erasers, of which the following is a specification.

The objects of this invention are to provide an eraser for draftsman, typewriters 10 and the like, which shall combine the properties of both a pencil eraser and an ink eraser; to enable either pencil eraser or ink eraser to be used practically alone or the two used simultaneously in combination of 15 any proportion between the whole of one and none of the other or none of the first and the whole of the second; to enable the combination of pencil and ink eraser to be made and adjusted instinctively or intuitively in use; to thus secure an eraser which 20 is adapted to various uses required of it, and to secure better erasing with less detriment to the paper; to secure such an eraser, which 25 differs greatly in form or appearance from erasers now on the market, and to obtain other advantages and results as may be brought out in the following description.

Referring to the accompanying drawings 30 in which like numerals of reference indicate the same parts throughout the several views,

Figure 1 is a side view of an eraser embodying my improved construction in its preferred form;

Fig. 2 is a sectional view of the same; 35 Fig. 3 is a side view of a modified form of my invention, and

Fig. 4 is a section thereof.

In the specific embodiment of the invention shown in said drawings, and referring 40 particularly to Figs. 1 and 2, reference numeral 1 indicates the disk-like body of my improved eraser, having at opposite sides thereof plates 2, 3 secured together by an eyelet 4 extending therebetween and passing 45 through the body 1, all as is usual in the well-known type of eraser which is commonly called "circular eraser."

The body or disk 1 of the eraser comprises a median layer 5 of pencil eraser and 50 on opposite sides of said median layer 5 are outside layers 6, 6 of ink eraser, all said layers being formed of any material known to the art such as rubber treated in the usual way to make pencil and ink erasers. 55 The marginal portion of the eraser which projects beyond the side plates 2, 3 there-

fore presents at its sides ink erasing material while at the extreme edge the pencil erasing material is exposed.

In using the eraser, the effect of practically all ink eraser may be secured by tipping the eraser flatwise almost onto either of its sides, while the effect of practically entire pencil eraser may be secured by standing the eraser upright on edge. Obviously 60 by tipping it at a greater or less angle into position intermediate those just stated, the combined effect of ink eraser and pencil eraser may be obtained in any desired proportion. The eraser can thus be adapted 65 to any kind of work which presents itself, and do such work effectively without injuring the paper. For instance, if a typewritten letter to be removed is very black the pencil eraser can first be employed to prevent smearing, and then the ink eraser used 70 to remove the letter changing gradually 75 back to the pencil eraser for smoothing and polishing.

In Figs. 3 and 4, 7 indicates the body portion 80 of an eraser comprising a middle layer 8 of ink erasing material and outside layers 9, 9 of pencil erasing material, the middle layer of ink erasing material being thick enough so that a sufficient surface of it is 85 presented at the periphery of the eraser. Obviously the use of this eraser would be the same as the preferred form already described, except that it would be tipped on its side for pencil erasing and stood upright 90 on edge for ink erasing. The preferred form is considered better, however, because the softer ink eraser usually wears away faster than the middle layer of tougher pencil erasing material and so the latter maintains 95 an edge on the eraser such as is particularly desirable in typewriter work.

The layers of my improved eraser may be secured together in any suitable manner known to those skilled in the art, as by vulcanizing, and while I have shown the eraser in the form of a circular eraser, obviously it might be otherwise made up. The side plates 2, 3 of the circular eraser serve nicely, however, to insure that the eraser is used 100 at and adjacent to its edge, so that the layers are worn back somewhat evenly.

In any event, the outer layers are exposed at their edges and outer marginal portions, while the middle layer is exposed only as said 110 outer layers are worn away. The thickness and material of the layers, that is of the outer

layers with respect to the middle layer, can be made to serve the particular purpose desired, it being understood that the proportion is always such that the outer layers 5 will wear away fast enough to expose the middle layer as desired. This always retains a sharp or tapered edge of the eraser and conduces to its most efficient use as set forth.

10. Having thus described the invention, what I claim is:

1. An eraser comprising a middle layer of erasive material and opposite outside layers of erasive material different from that 15 of said middle layer, all said layers being firmly united to sustain one another and the outer layers being so proportioned with respect to the middle layer as that said outer layers will be worn away at their edges and 20 outer marginal portions by use faster than the

middle layer to expose the middle layer as required and always retain a tapered or sharpened edge on the eraser.

2. An eraser comprising a middle layer of erasive material and opposite outside layers 25 of erasive material different from that of said middle layer but alike in both of themselves, all said layers being firmly united to sustain one another and the outer layers being so proportioned with respect to the 30 middle layer as that said outer layers will be worn away at their edges and outer marginal portions by use faster than the middle layer to expose the middle layer as required and always retain a tapered or sharpened 35 edge on the eraser.

WELDON ROBERTS.
